UNITED STATES PATENT OFFICE.

JOHN H. GOSS, OF WATERBURY, CONNECTICUT, ASSIGNOR TO THE SCOVILL MANUFACTURING COMPANY, OF SAME PLACE.

VALVE FOR INFLATION.

SPECIFICATION forming part of Letters Patent No. 629,786, dated August 1, 1899.

Application filed May 8, 1899. Serial No. 716,012. (No model.)

To all whom it may concern:

Be it known that I, JOHN H. GOSS, a citizen of the United States, residing at Waterbury, in the county of New Haven and State of Connecticut, have invented a certain new and useful Improvement in Inflation and other Valves, of which the following is a full, clear, and exact description.

This invention relates more especially to 10 that class of valves which are used for inflating the pneumatic tires of bicycles; and the invention is particularly designed for use in connection with those valves which comprise a shell or casing to be applied to a rubber 15 cot and containing a spring-pressed plunger, which normally closes the valve against the escape of the air from within the tire and which valve is held in place by a hollow screw-plug inserted in the inner end of the shell or 20 casing. The shell or casing is provided with a removable cap and is also provided with an internal screw-thread, to which may be applied the inflating apparatus when the cap is removed.

25 The invention consists of a hollow screw-plug formed of sheet metal; and the invention also consists in the combination of such a hollow screw-plug with a valve of the character described or of other suitable construction, all as I will proceed now more particularly to set forth and finally claim.

In the accompanying drawings, illustrating my invention, in the several figures of which like parts are similarly designated, Figure 1 35 is an elevation of an inflation-valve of substantially the construction illustrated in the patent granted to the Scovill Manufacturing Company as my assignees on September 20, 1898, No. 610,985. Fig. 2 is a longitudinal 40 section thereof, these two views showing the hollow plug of this invention applied. Fig. 3 is an elevation of the hollow plug detached and containing a knurled head. Fig. 4 is an elevation of the plug detached and showing 45 it without the knurling of the head. Fig. 5 is a vertical section which illustrates the two plugs of Figs. 3 and 4.

The shell or casing *a* may be provided with grooves *b* to assist in applying the valve to

the rubber cot of the tire, and it is also provided with a valve-seat *c*, an external screw-thread *d* to receive the cap *e*, of any suitable construction, and the internal screw-threaded chamber *f* to receive the inflation-pump connection. *g* is a valve or plunger constructed, preferably, in accordance with the patent hereinbefore referred to and seating against the seat *c* and normally held thus seated by the spring *h*. The inner end of the shell or casing is provided with a screw-thread *i* to receive the plug *k*, which plug serves to hold the spring in place, and consequently the valve or plunger. This plug *k* is made hollow for the passage of the air from the pump into the tire. Heretofore such plugs usually have been made of solid wire or rod bored or otherwise treated to adapt them for use in connection with inflation-valves of this general character. I have found that these plugs may be made very 65 much more economically by producing them from sheet metal properly manipulated to provide a rounded or globular head *k'*, which, as shown in Fig. 3, may be knurled, or, as shown in Fig. 4, may be left plain or not 70 knurled, and a shank portion *k*², which is externally screw-threaded to adapt it to coöperate with the screw-thread *i* within the shell or casing of the valve. The inner end of this shank is curved inwardly, as at *k*³, and 75 perforated at *k*⁴. By curving in the inner end of the plug it is more easily guided into coöperation with the screw-thread of the shell, and by making the head curved or of approximately globular form the valve as a 80 whole is more easily entered into the cot or other device by which the said valve is connected with the tire or other object to be inflated.

The plug is screw-threaded into the shell 90 or casing in order to be readily removable for obtaining access to the valve mechanism contained within said shell or casing.

I do not limit my invention to a plug produced solely from sheet metal, although a 95 hollow sheet-metal plug is the preferred construction and constitutes one portion of this invention. It is within my invention to

make of any suitable blank a plug having a substantially or approximately globular head with or without knurling.

What I claim is—

- 5 1. An inflation-valve, comprising essentially a shell or casing, an internal valve mechanism, a cap at one end and a removable plug at the other end, the said plug having an approximately globular end or head, 10 a screw-threaded shank and an inwardly-curved and perforated end, substantially as described.
- 15 2. A valve for inflation, of any approved construction, having a plug screw-threaded into one end thereof and provided with an approximately globular head, the said plug being formed of sheet metal, substantially as set forth.
- 20 3. A plug for inflation and other valves, constructed of sheet metal and having a screw-

threaded shank and an approximately globular head, substantially as described.

4. A plug for inflation and other valves, constructed of sheet metal and having a screw-threaded shank and an approximately 25 globular head, the exterior of the said head being knurled, substantially as described.

5. A plug for inflation and other valves, constructed of sheet metal and having a screw-threaded shank terminating in an inwardly-curved perforated end, and an approximately globular head, substantially as 30 described.

In testimony whereof I have hereunto set my hand this 6th day of May, A. D. 1899.

JOHN H. GOSS.
